UNITED STATES PATENT OFFICE.

WILLIAM J. BAIN, OF PIERCE CITY, MISSOURI.

CONDIMENT-HOLDER.

No. 824,058.

Specification of Letters Patent.

Patented June 19, 1906.

Application filed October 20, 1905. Serial No. 283,684.

To all whom it may concern:

Be it known that I, WILLIAM J. BAIN, a citizen of the United States, residing at Pierce City, in the county of Lawrence and State of Missouri, have invented a new and useful Condiment-Holder, of which the following is a specification.

This invention relates to condiment-holders, and has for an object to provide a device of the class embodying new and improved features of convenience, reliability of action, sightliness, and efficiency.

It is well known that some of the condiments in common use, notably common salt, are hygroscopic to such a degree that during humid weather they become so moist as to make their operation in shakers a matter of great annoyance.

It is an object of this invention to provide a condiment-holder embodying improved means for stirring and beating the contents of the holder and scraping the usual perforate top and feeding the contents.

With these and other objects in view the present invention consists in the combination and arrangement of parts, as will be herein-after fully described, shown in the accompanying drawings, and particularly pointed out in the appended claims.

In the drawings, Figure 1 is a vertical section through the condiment-holder, and Fig. 2 is a perspective view of the blades thereof.

Like characters of reference indicate corresponding parts in both figures of the drawings.

The improved condiment-holder forming the subject-matter of this application comprises a receptacle 10 of any approved size, form, and material and having a perforate cap 11 secured thereon by the screw-threads, as shown, or by means of any latch, catch, or other approved means.

Within the receptacle is mounted a spindle 12, journaled at one end, as by the trunnion 13, in a central opening in the cap and with the opposite end, as 14, extending through the bottom of the receptacle and provided with any approved means to rotate the spindle, here shown as a crank-arm 15, with a skirt 16

formed upon the receptacle to accommodate the rotating means.

Adjacent the trunnion 13 any approved number of blades 17 18 are rigidly secured to the spindle 12 and in contact with the cap 11. The blades are arranged in pairs, as 17 18, and are shaped similar to screw-propeller blades, but the individuals of the pairs reversely inclined to the cap, so that turned in the usual direction the forward edge of blade 17 is in contact with the cap to scrape away accumulations, while the forward edge of the blade 18 following is spaced from the cap and the rearward edge in contact, so that the blade 18 serves to feed the contents and force it through the perforations opened and cleared by the preceding blade 17. If the motion is reversed, the blade 18 becomes the scraper and the blade 17 the feeder.

The spindle 12 is provided with any approved number of spaced radial arms or fingers 19 and other radial arms or fingers 20, extending from a U-shaped bar 21, disposed in vertical grooves 23 within the receptacle 10 and adapted to be slid longitudinally within these grooves either to place the arms in or remove them from position within the receptacle. These arms coöperate with the rotating arms, so as to agitate the contents of the receptacle and break up any lumps contained therein.

Having thus described the invention, what is claimed is—

1. A condiment-holder comprising a receptacle, a beater mounted to rotate therein, a removable device mounted within the receptacle, and inwardly-directed arms upon said device and adapted to coöperate with the beater.

2. A condiment-holder comprising a grooved receptacle, having a closure, a series of rotatable beater-arms within the receptacle, means movable therewith for scraping material from the closure and forcing it therethrough, a rod detachably seated in the grooves and arms extending from the rod into the receptacle and coöperating with the rotatable beater-arms.

3. A condiment-holder comprising a re-

ceptacle having grooves therein, a rod removably seated in the grooves, converging arms upon the rod and a beater mounted to rotate within the receptacle to coöperate with the arms.

4. A condiment-holder comprising a receptacle having grooves in the wall thereof, a rod removably seated in the grooves, arms extending from the rod, and a beater mount-

ed to rotate in the receptacle and to coöperate with the arms.

In testimony that I claim the foregoing as my own I have hereto affixed my signature in the presence of two witnesses.

WILLIAM J. BAIN.
